(57) **CLAIM**

The ornamental design for a shoe, as shown and described.

DESCRIPTION

FIG. 1 is a front view of a shoe showing our new design; FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front, top, and right side perspective view thereof; FIG. 8 is a rear, bottom, and left side perspective view thereof;

FIG. 9 is an enlarged end view taken along line 9-9 of FIG. 1; and,

FIG. 10 is an enlarged end view taken along line 10-10 of FIG. 1.

The broken lines shown in the figures depict portions of the shoe that form no part of the claimed design.

1 Claim, 8 Drawing Sheets
